CIRCUIT BREAKER

John D. Hilliard, Glens Falls, N. Y.

Application October 17, 1942, Serial No. 462,328

5 Claims. (Cl. 200—150)

This invention relates in general to circuit breakers of the type in which cooperating contacts are separable in insulating fluid and relate particularly to an improved means for enclosing the cooperating contacts of such a circuit breaker.

In prior art circuit breakers of the so-called explosion pot type, the cooperating contacts are substantially enclosed when they make and also when they break. When the cooperating contacts make, there is an instantaneous generation of gas which is equivalent to an explosion and in some cases the contacts are driven apart and sustained arcing results. Also, when very large currents are to be interrupted, the rate of gas generation is so great that excessive chamber pressure results and, in order to secure safe operation, top venting of the chamber has been resorted to.

It is therefore an object of the present invention to provide a so-called explosion pot circuit breaker that will avoid the above disadvantages.

It is a further object of the present invention to provide an explosion pot type of circuit breaker with contacts which will make and break substantially at the throat of the explosion pot.

It is also an object of the present invention to provide in an enclosed type of circuit breaker, a means whereby the arc, drawn upon separation of the contacts, is almost instantaneously subjected to a gas and oil blast, thereby promptly extinguishing the arc.

Objects and advantages other than those above set forth will be apparent to those skilled in the art when read in connection with the accompanying drawing, in which:

Fig. 1 is a sectional plan view of a circuit breaker embodying the present invention;

Fig. 2 is a sectional plan view of a modification of the invention shown in Fig. 1; and

Fig. 3 illustrates a modified contact structure usable in the circuit breaker of Fig. 2.

In Fig. 1 is shown a circuit breaker having a tank 5 substantially filled with any suitable insulating and arc extinguishing fluid of which oil is an example. The cover 6 has two bushings 7 therethrough, one of which carries a conductor 10 carrying the stationary contact 14, and the other of which carries a conducting rod 16. One end of a movable bridging member 9 is conductively connected to the rod 16 in slidable relation thereto by means of the rollers 15, and the other end thereof supports the movable contact 11. The bridging member 9 is moved by the operating rod 8 to make and break the cir-

cuit at the contacts 11 and 14. The operating rod 8 is insulated from the bridging member 9. Mounted on the conductor 10 is a contact enclosing pot 17. This pot 17 is slidably mounted and is biased to its position shown by a spring 13. A shoulder on the stationary contact 14 limits the downward movement of the pot 17 to the position shown. When the operating rod 8 is lifted and the bridging member 9 is thereby raised, the stops 12 on the member 9 engage the bottom of the pot 17. In this position the upper end of contact 11 is in the throat 18. The pot 17 is lifted against the pressure of the spring 13 by further movement of rod 8 and consequently the contacts 11 and 14 make in or adjacent the throat 18 of the pot at a point determined by the relative extent of members 11 and 12 from the member 9.

The making of the contacts 11 and 14 at the throat 18 provides several advantages. Any gas generated by an arc drawn upon making of the contacts can immediately escape, for there is very little oil which must be accelerated to provide for such escape. This is important for while the gas generated moves at a speed of the order of 8000 feet per second, the movement of oil is of the order of 150 feet per second. Thus excessive pressure in the pot 17 is prevented.

Also, any arc, drawn when the contacts 11 and 14 make, is quickly extinguished, for such arc is drawn in the throat 18 where the most efficient deionization and blast action is obtained. The throat 18 of itself forms a small pressure chamber in which the arc is drawn and extinguished by the blast action of the oil fed to the arc from the pot 17.

Contacts 11 and 14 are similarly in the throat 18 when the circuit breaking arc is drawn. When the circuit is broken by a downward movement of the rod 8, an arc is drawn and maintained at the throat 18, where it is subjected most efficiently to the gas and oil blast and thereby quickly extinguished.

As the pot 17 follows the downward movement of the bridging member 9, due to the action of the spring 13, the arc is in effect drawn upwardly into the pot 17. The lower end of the arc is adjacent to or in the throat 18 at all times during the downward movement of the pot 17. This permits the fresh, cool oil to be utilized for deionization and blasting of the arc, and provides an automatic pressure relief. If the pressure becomes too great, the pot 17 will be forced upward against the action of spring 13, thereby

providing less arc in the pot and reducing the pressure.

The circuit breaker shown in Fig. 2 is a two-break circuit breaker in which the cover 6 supports the bushings 19, which in turn support the conducting studs 20. Slidably mounted on the conducting studs 20 are pots 21 resiliently biased to a downward position by means of springs 22. The bridging member 25 carried by and movable with the operating rod 24, supports a stop member 26 which functions to push the pot against the action of springs 22 to the position shown upon upward movement of the operating rod 24.

The movable contacts 29 are slidably mounted on guides 28 supported on members 27 conductively carried by the bridging member 25. The movable contacts 29 are biased upwardly by springs 31 and are electrically connected to the members 27 by means of pigtails 30. As the contacts are movable relative to the bridging member 25 and stop member 26 and are spring biased, a predetermined contact pressure is maintained between the movable contacts 29 and the stationary contacts formed by the ends of studs 20. Stops 23 on the studs 20 limit the downward movement of the pots 21.

The arc extinguishing action of this modification is similar to that of the circuit breaker shown in Fig. 1, and similar advantages are obtained from such action. However, the pressure relieving action afforded as in the embodiment of Fig. 1, by forcing of the pot 21 upward against the action of springs 22, is additionally found in the forcing of contact 29 downward against the bias of spring 31. This action provides rapid extension of the arc and rapid clearance of the pressure gases in the throat.

A modification of the contact structure shown in Fig. 2 is illustrated in Fig. 3. The moving contact 41 is hollow and is slidably mounted in and guided by the conducting member 40 and the pot operating member 43. A spring 42 provides the desired contact pressure. The stop 44 becomes effective to transmit downward movement of the bridging member 25 to the movable contact 41. A pigtail (not shown) or other suitable means may be utilized to conduct current from contact 41 to the member 40.

Arc extinguishing action similar to that of the embodiments of Figs. 1 and 2 is obtained in Fig. 3, as the contact making and breaking is always in the throat or closely adjacent thereto. The point of contact can be varied by relative dimensioning and positioning of the stops 43 and 44. Thus the throat action is effective from the inception of arcing and the arc is drawn back into the pot, preventing forcing of the oil out of the pot prior to the arc being in the throat.

Although but several embodiments of the invention have been illustrated and described, it will be apparent to those skilled in the art that various changes and modifications may be made therein without departing from the spirit of the invention or from the scope of the appended claims.

It is claimed and desired to secure by Letters Patent:

1. In a fluid break circuit breaker, a pair of fixed contacts, a pair of cooperating movable contacts, a bridging member connecting said

pairs of cooperating contacts in series, means for slidably supporting said movable contacts on said bridging member, pressure chambers each enclosing one of said fixed and one of said movable contacts and provided with an opening therein into which said fixed and said movable contacts may extend, means whereby said chambers are slidably supported relative to said first contacts, means comprising stops on said bridging member for transmitting movement thereof to said chamber, and means dependent upon the extent of said stops from said bridging member for positioning the make and break point of said contacts in said pressure chamber, in said opening or external to said chamber and to said opening.

2. In a circuit breaker, a fixed contact, a chamber enclosing said fixed contact, insulating and arc extinguishing fluid surrounding said contact in said chamber, a throat opening in said chamber, a second contact movable relative to said fixed contact and cooperable to make and break therewith, an operating member for moving said second contact relative to said chamber, means for supporting said chamber for movement relative to said fixed contact, and means operative to stop said relative movement between said second contact and said chamber when said second contact is in said throat opening.

3. In a circuit breaker, a fixed contact, a chamber enclosing said fixed contact, insulating and arc extinguishing fluid surrounding said contact in said chamber, a throat opening in said chamber, a second contact movable relative to said fixed contact and cooperable to make and break therewith, an operating member supporting said second contact for movement relative to said chamber and for movement relative to said operating member, and means operative to stop said relative movement between said second contact and said chamber when said second contact is in said throat opening.

4. In a circuit breaker, a fixed contact, a chamber enclosing said fixed contact, insulating and arc extinguishing fluid surrounding said contact in said chamber, a throat opening in said chamber, a second contact movable relative to said fixed contact and cooperable to make and break therewith, an operating member supporting said second contact for movement relative to said chamber and for movement relative to said operating member, and means operative to stop said relative movement between said second contact and said chamber when said second contact is immediately adjacent said throat opening.

5. In a fluid break circuit breaker, a fixed contact, a cooperating movable contact, a member for operating said movable contact, means for supporting said movable contact on said operating member for relative movement therebetween, a pressure chamber enclosing said fixed contact and supported for movement relative thereto and provided with a throat opening therein into which said fixed and said movable contacts may extend, means for stopping relative movement between said movable contact and said chamber and for determining the make and break points of said contacts relative to said throat opening.

JOHN D. HILLIARD.
